T. M. WILKINS.
PRESSURE REGULATOR.
APPLICATION FILED AUG. 14, 1918.

1,294,586.

Patented Feb. 18, 1919.

Invention:

Thomas M. Wilkins
By J. C. H. M. Steigens
Atty.

UNITED STATES PATENT OFFICE.

THOMAS M. WILKINS, OF EAST RANDOLPH, NEW YORK.

PRESSURE-REGULATOR.

1,294,586.

Specification of Letters Patent. Patented Feb. 18, 1919.

Application filed August 14, 1918. Serial No. 249,806.

To all whom it may concern:

Be it known that I, THOMAS M. WILKINS, a citizen of the United States, residing at East Randolph, in the county of Cattaraugus and State of New York, have invented certain new and useful Improvements in Pressure-Regulators; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to improvements in pressure regulators, and particularly to that class of such regulators as are used for regulating and equalizing the steam pressure to multiple engines so that they will operate in unison.

The features of my invention consist substantially in the features of construction and arrangement of the mechanism hereinafter set forth and described and illustrated in the accompanying drawings, in which:—

Figure 1, is a view partially in elevation and partially in section illustrating my improved pressure regulator.

Fig. 2, is a plan view of a section of my improved diaphragm.

Fig. 3, is a plan view of the peripheral ring resting upon the periphery of said diaphragm section.

Fig. 4, is a transverse section of the same.

Fig. 5, is a plan view of a disk resting upon the central part of said diaphragm section.

Fig. 6, is a side view in elevation of the same.

Fig. 7, is a detail illustrating a steam distributor.

Fig. 8, is an end view in elevation of the steam supply inlet.

Fig. 9, is a plan view of a perforated sieve for the supply inlet.

Fig. 10, is a detail of the rod connecting the control valve and the diaphragm mechanism.

Fig. 11, is a view in elevation of the disk engaging the top of the rod (Fig. 10) and contacting with the central part of the diaphragm section (Fig. 2).

In these drawings illustrating my invention the frame of my device may be of any suitable type, and comprises substantially a

diaphragm mechanism support at its upper end with a fluid supply thereto, and a valve mechanism of any suitable type, and connections to a fluid pressure supply, and connections suitable to distribute the fluid supply in the lower part of said frame.

The diaphragm case A is preferably supported on the top of a tube k, the lower end of which is secured to a yoke p, the lower end of which is secured to the top of the valve case g.

In the diaphragm case A I mount a diaphragm section, (Fig. 2) comprised substantially of a peripheral section a, and a central section a', concentrically connected by means of wire loops a². Resting upon the top of the part a there is a ring C, having an inner flange c which covers the holes a³ in the ring a, in which the loops a² are secured, as clearly shown in Fig. 1.

Resting upon the top of central section a' there is a disk b having a stud b' thereon, which extends down through a central opening a⁴ in the disk a'. On the periphery of the disk b there is a flange b², which overlaps and covers the connection of the wire loops a², with the disk a', as shown in Fig. 1. On the top of the disk mechanism above described, I secure a flexible disk N, preferably of rubber, or of other suitable flexible material, and above this disk N there is a steam pipe connection N', leading to a steam supply of maximum pressure.

Under the central disk a' I place the disk d' (Fig. 1) through which the stud b' extends downward into an opening in the upper end of the thrust rod d, the lower end of which rod is secured to the valve stem g'. Around this rod d there is a tube k, the upper end of which is screwed into the lower part of the diaphragm case A, and the lower end thereof into the upper end of the yoke p; and in the upper part of the tube k, just below its junction with the diaphragm case A there are slots k', in which a transverse pin n in the rod d, operates to limit the vertical movement thereof.

Mounted on the tube k there is a spiral spring l, the upper end of which engages the cross pin n, and the lower end a washer o, resting upon an adjusting nut h, preferably of hand wheel form, whereby the tension of the spring l can be adjusted. The washer o is preferably provided with ball 110

bearings of suitable type engaging the nut h so that the operation thereof will not tend to distort the spring l .

- The valve g is of any suitable type, and 5 has one end g^2 of the case thereof open to the atmosphere. Opposite this opening I secure the inlet connection G , which comprises substantially a nipple e having a restricted inlet opening e' through which 10 steam or other fluid is supplied. This opening is preferably provided at its outer end with a perforated disk f , which prevents impurities being carried into it and obstructing the restricted opening e' . Between the 15 restricted part e' of the opening, and the valve case g , the opening in the nipple e is enlarged, and the distributing device S secured thereto by a screw threaded joint, or in other convenient manner.
- 20 In operation steam or fluid is supplied to the diaphragm case A through the pipe N' , at maximum pressure; and the steam is supplied to the restricted opening e' at the normal working pressure at which it is de- 25 sired to use it, and distributed through the connection S to the pressure controlled throttle valves on the engines which it is designed to operate; and when the operating pressure varies at any time, the dia- 30 phragm mechanism operates to open or close the regulating valve as may be required to control and equalize such pressure and maintain it at its normal status.

I have herein described my apparatus as utilized in connection with steam engines; 35 it is obvious, however, that it can be used with equal facility to control the pressure and flow of gases and other fluids, as may be required, without departing from the spirit of the invention. 40

Having thus described my invention so as to enable others to construct and utilize the same, what I claim as new and desire to secure by Letters-Patent is:—

1. In a pressure regulator diaphragm mechanism, a diaphragm support comprising substantially an annular disk having holes in the inner edge, a central disk having holes in its outer edge, and radial loops extending from the holes in the ring to the 45 holes in the disk, substantially as set forth.
2. In a pressure regulator mechanism, a diaphragm case, a diaphragm mechanism mounted therein comprising substantially an annular ring having holes in its inner edge, 50 a central disk having holes in its outer edge, radial loops connecting the holes in the ring and disk, a collar resting on said ring, a central supporting disk resting on the central disk secured in said ring, and a 55 fluid impervious flexible diaphragm resting upon said collar and central supporting disk, substantially as set forth.

In testimony whereof I affix my signature.

THOMAS M. WILKINS.
